US00D862151S

(12) **United States Design Patent** (10) Patent No.: **US D862,151 S**
(45) Date of Patent: ** Oct. 8, 2019

(54) **INDUCTION HEATING RANGE**

(71) Applicant: **LG ELECTRONICS INC.**, Seoul (KR)
(72) Inventors: **Inhwan Ryu**, Seoul (KR); **Hongsik Kwon**, Seoul (KR); **Sooyeon Kim**, Seoul (KR); **Songyi Han**, Seoul (KR)
(73) Assignee: **LG ELECTRONICS INC.**, Seoul (KR)

(**) Term: **15 Years**

(21) Appl. No.: **35/505,514**

(22) Filed: **Jul. 19, 2018**

(80) **Hague Agreement Data**

Int. Filing Date: **Jul. 19, 2018**

Int. Reg. No.: **DM/102284**

Int. Reg. Date: **Jul. 19, 2018**

Int. Reg. Pub. Date: **Aug. 24, 2018**

(51) **LOC (12) Cl.** **07-02**

(52) **U.S. Cl.**

USPC **D7/346**

(58) **Field of Classification Search**

USPC D7/323, 336, 337, 339, 340, 346, 347, D7/348, 402-409, 387

CPC H05B 6/1209; H05B 1/0266; H05B 2206/02; F24C 7/043; F24C 7/082

(57) **CLAIM**

The ornamental design for induction heating range, as shown and described.

DESCRIPTION

1. Induction heating range

1.1 : Perspective

1.2 : Front

1.3 : Back

1.4 : Left

1.5 : Right

1.6 : Top

1.7 : Bottom
